UNITED STATES PATENT OFFICE.

HUBERT E. HARRIS AND LEE O. SWAIM, OF ATLANTA, GEORGIA, ASSIGNEES OF ONE-
THIRD TO J. F. PICKARD, OF ATLANTA, GEORGIA.

NOISELESS BLOWER FOR LOCOMOTIVES.

1,416,954.

Specification of Letters Patent. Patented May 23, 1922.

Application filed June 23, 1919. Serial No. 306,013.

To all whom it may concern:

Be it known that we, HUBERT E. HARRIS and LEE O. SWAIM, citizens of the United States, residing at Atlanta, in the county 5 of Fulton and State of Georgia, have invented certain new and useful Improvements in Noiseless Blowers for Locomotives; and we do hereby declare the following to be a full, clear, and exact description 10 of the invention, such as will enable others skilled in the art to which it appertains to make and use the same, reference being had to the accompanying drawings, and to the letters and figures of reference marked 15 thereon, which form a part of this specification.

This invention relates to new and useful improvements in noiseless blowers for use in connection with locomotives, and consists in 20 the provision of means whereby the smoke stack of the engine may be caused to draw smoke to the limit of its capacity by jetting steam through a plurality of nozzles disposed at different angles, and thereby distributing the suction force of the entire area 25 within the stack.

Heretofore it has been common to inject through a single nozzle steam into the smoke stack of an engine for the purpose accelerating the draft from the boiler furnace, and which is necessary when the locomotive stops the supply of steam being turned on by the fireman for the purpose of creating a draft while the locomotive is standing and 35 which creates a deafening noise, which is very objectionable.

It is the object of the present invention to avoid this nuisance and at the same time to cause the smoke to be drawn through the 40 stack at its maximum capacity and practically noiseless.

The invention comprises a simple and efficient device of this character having various details of construction, combination and 45 arrangement of parts which will be herein-after fully described, shown in the accompanying drawings and then specifically defined in the appended claims.

Our invention is illustrated in the accompanying drawings which, with the letters of reference marked thereon, form a part 50 of this application, and in which:

Figure 1 is a central vertical longitudinal sectional view through the forward portion of the boiler of a locomotive. 55

Figure 2 is a sectional view on line 2—2 of Figure 1, and

Figure 3 is an enlarged detail view.

Reference now being had to the details of the drawings by letter:

A designates the usual boiler of a locomotive and B the stack. Said boiler is provided with the usual table sheet C extending horizontally across the forward portion of the boiler and D designates a draft sheet 65 projecting downward at an angle as shown, and extending the width of the chamber in which it is positioned. A wire netting E is interposed between the forward ends of the table sheet and the top of the boiler and 70 through which the smoke is drawn by draft into the portion of the chamber above the table sheet which communicates with the smoke stack.

The exhaust nozzle F is positioned centrally in alinement with and spaced apart a slight distance from the stack in the usual manner. A tubular pipe H is supported upon the table sheet about the upper portion of the nozzle spaced apart from the upper 80 end thereof a slight distance, the said tubular pipe being fastened securely in place in any suitable manner and provided with a plurality of nozzles K which are disposed preferably at inclinations, so that jets of 85 steam directed through the same are collimated into conoidal formation with the apex within the petticoat of the stack, and substantially parallel with its sides.

A steam supply pipe N leads to and communicates with said circular pipe which has said nozzles and which is adapted to communicate with a steam bug, not shown, the supply of steam being regulated through a valve mechanism within control of the fireman in the cab of the locomotive. 90 95

In operation, the natural draft of the smoke takes the direction indicated by the arrows in Figure 1 of the drawings, a natural draft being created when the locomotive is under steam. 100

When the locomotive stops and it is desired to maintain an artificial draft, the operator by turning on the live steam may

cause the same to be jetted through the nozzles into the smoke stack and thereby distributing the suction area caused by the injection of the steam into various parts of 5 the smoke stack, and which will cause smoke from the furnace to be drawn through the stack to the limit of its capacity, and owing to the breaking up of the jets of steam by their being directed at different angles to 10 one another into the smoke stack, the noise incident to the escaping steam is muffled and reduced to a minimum.

By the provision of the apparatus embodying the features of our invention, it has 15 been demonstrated by experience that the combustion of the fuel is greatly accelerated, and effecting also an appreciable saving of fuel.

What we claim to be new is:

20 1. The combination with a locomotive smoke box of a stack leading therefrom and provided with a funnel at its inlet end and a jet ring the center of which lies in the extended axis of the stack, said jet ring 25 provided with nozzles inclined toward the

axis in position to deliver actuating fluid in directions parallel to the walls of the funnel and lying in a cone the apex of which is within the stack.

2. The combination with a locomotive 30 smoke box of a stack leading therefrom and provided with a funnel at its inlet end, a main exhaust nozzle, an unpartitioned tubular jet ring the center of which lies in the extended axis of the stack, and a passage be- 35 tween the main nozzle and the jet ring, said jet ring provided with nozzles in juxtaposition to the funnel and inclined toward the axis in position to deliver actuating fluid in directions parallel to the walls of the funnel and lying in a cone the apex of which is within the stack.

In testimony whereof we hereunto affix our signatures in presence of two witnesses.

HUBERT E. HARRIS,
LEE O. SWAIM.
